UNITED STATES PATENT OFFICE.

WILLIAM H. SAUVAGE, OF NEW YORK, N. Y., ASSIGNOR, BY MESNE ASSIGNMENTS, TO GOULD COUPLER COMPANY, OF NEW YORK, N. Y.

SLACK ADJUSTER.

Application filed November 25, 1921. Serial No. 517,630.

To all whom it may concern:

Be it known that I, WILLIAM H. SAUVAGE, citizen of the United States, residing at New York, in the county of New York and State 5 of New York, have invented certain new and useful Improvements in Slack Adjusters, of which the following is a specification.

This invention relates to improvements in slack adjusters and more particularly to 10 a slack adjuster complete in itself and applicable to brake rigging of railway cars and particularly to truck brake rigging incorporated with the brake beam strut.

The invention will accordingly be herein- 15 after described with relation to such application although it is to be understood that without material modification various features are applicable to other installations.

One of the objects of the present invention 20 is to provide a simple and practical slack adjuster as an independent unit, which may be readily installed and applied to truck brake rigging now in use without material modification.

25 A further object is to provide an automatic slack adjuster that does not interfere with any of the natural gravitation laws of the present brake operation and one which will permit in every case a perfect freedom 30 for the hangers attached to the brake beams to go into full released position due to the angularity of the hangers and the weight of the levers, beams, brake shoe and brake shoe heads.

35 A further object is to provide a slack adjuster of the above general type which will, of course, ensure uniform positive travel at all times, provide the proper brake shoe clearance as well as one which will be reliable, durable and efficient under all conditions.

40 Other objects will be in part obvious and in part hereinafter pointed out.

The invention accordingly consists in the 45 features of construction, the combination of elements and the arrangement of parts which will be exemplified in the device hereinafter described, and the scope of the application of which will be indicated in the appended claims.

50 In the accompanying drawings—

Figure 1 shows semi-diagrammatically and in partial sectional elevation one of the various possible embodiments of the 55 present invention and while this invention

will, as above stated, be hereinafter described in its relation or application to the truck brake rigging, it is, of course, applicable to other parts of the foundation brake rigging; 60

Figure 2 is a detailed transverse sectional view.

Referring now to the drawings in detail, 5 denotes a live lever preferably made in two parts, riveted at 6 and bifurcated at its lower 65 end 7, as shown more clearly in Figure 2. This live lever has pivotally connected at its upper end at the point 8 a pull rod 10 connected with any suitable source of power for applying the brakes; the live lever is 70 guided in its movement by a guide bar 11 of well known construction. The lower end of the live lever has pivotally connected therewith at the point 12 a push rod 13, the 75 opposite end of which is pivotally connected at 14 with the lower end of the dead lever 15, the upper end of the dead lever being adjustably connected to a fixed bracket 16.

The slack adjuster mechanism or unit is 80 preferably directly associated with the brake beam construction and there is indicated at 17 the transverse portion of the brake beam and at 18 the rectangular shaped tension member, which connects the ends of the brake beam and is separated from the parts 17 by 85 means of a strut 20 preferably in the form of a round steel bar. The bifurcated portion of the live lever carries a dog housing member 21 having trunnions 22 passing through the bifurcated portion, as shown in Figure 2, 90 and within the housing are a plurality of dogs 23 having holes through their central parts with hardened edges and through which the rod 20 passes, as well, of course, as through the ends of the dog housing member 95 21. These dogs are normally held in canted position by means of a coiled spring 24 whereby they have a biting engagement with the rod 20. It will thus be seen that as the 100 brakes are applied these dogs will grip the rod 20 and urge the brake beam toward the left to apply the brakes.

Mounted upon this same rod is a second dog housing 25 containing one or more dogs 26 of the same general type as the dogs 23 and held in canted position by means of a spring 27. The lower part of this dog housing is provided with two holes 28 through which the take up rod 30 is adapted to pass. This rod 30 is pivotally connected at the 105 110

point 31 with the live lever between the trunnions 22 and the pivot point 12 and the opposite end is threaded to receive lock nuts 32 spaced apart from the side wall of the 5 dog housing 25, a distance equal to the desired predetermined lost motion for permitting brake shoe clearance 33.

In operation, when the live lever moves 10 towards the left in the direction of the arrow, pivoting on the trunnions 22, the lower end of the live lever moves towards the right and through the bottom rod 13 coacts with the dead lever 15 to carry the brake shoes into engagement with the peripheries of the 15 wheels. Should the normal movement of the live lever exceed the lost motion provided for by the lock nuts 32 and indicated at 33, the take up box or dog housing 25 will be moved along the rod 20 against the 20 action of a coiled spring 34 interposed between the two dog housings and place this spring under compression to the extent of excess movement of the live lever. On release of the brakes, this spring 34, being under compression, will force the main dog housing or permanent take up and holding device 21 relatively towards the right to the same extent that the spring 34 was compressed during the application of the brakes, 30 and the adjustment of the nuts 32 can be made to suit the travel required for the live lever in order to maintain predetermined piston travel. This progression of the temporary and permanent take up and holding 35 means represented by the dog housings 21 and 25, continues until the brake shoes are entirely worn out. Then, in order to release the adjuster, an operator inserts a rod with projections thereon into the dog housings 40 so as to trip the dogs in both housings and move the same to a position at right angles to the axis of the rod 20, the entire mechanism then may be moved bodily toward the left until they reach the position 45 shown in Figure 1. Then, on the first application of the brakes, the entire truck brake rigging will be automatically adjusted to the proper position to insure the desired 50 brake shoe clearance and uniform piston travel thereafter.

It will thus be seen from the above that the present invention provides a simple and practical slack adjuster, complete in itself, and one which does not require or depend 55 in any way upon release springs to properly return to normal position on release of the brake. The entire mechanism may be easily and quickly substituted for other equipment or applied to truck brake construction now 60 in general use without material modification. The live lever with its associated parts may be manufactured and assembled and all that is required is to connect the opposite 65 ends of the live lever to the pull rod 10 and the bottom rod 13.

As many changes can be made in the above construction and many apparently widely different embodiments of the invention can be made without departing from the scope thereof, it is intended that all matter contained in the above description or shown in the accompanying drawing shall be interpreted as illustrated and not in a limiting sense. 70

I claim:

1. In a slack adjuster, in combination, a bifurcated live lever, a permanent take up and holding means trunnioned in the bifurcated portion of the live lever, a brake beam having a strut associated with said permanent takeup and holding means, and means for progressively moving said take up and holding means along said strut as the brake shoe or wheel wear occurs, to thereby insure uniform piston travel and brake shoe 85 clearance.

2. In an automatic slack adjuster in combination, a brake beam having a tension member, a strut interposed between the beam and tension member, a live lever having a bifurcated portion enclosing said strut, and permanent and temporary take up and holding means mounted upon the strut and associated with the live lever, one of said means being operative on application of the brakes to temporarily take up the slack and operate upon the other of said means to permanently take up the slack on release of the brakes. 90

3. In an automatic slack adjuster, in combination, a brake beam having a tension member, a strut interposed between the beam and tension member, a live lever having a bifurcated portion enclosing said strut, and permanent and temporary take up and holding means mounted upon the strut and associated with the live lever, one of said means being operative on application of the brakes to temporarily take up the slack and operate upon the other of said means to permanently take up the slack on release of the brakes, said temporary take up means including a housing and a spring actuated dog therein, 105 coacting with the strut. 110

4. In an automatic slack adjuster, in combination, a brake beam having a tension member, a strut interposed between the beam and tension member, a live lever having a bifurcated portion enclosing said strut, and permanent and temporary take up and holding means mounted upon the strut and associated with the live lever, one of said means being operative on application of the brakes to temporarily take up the slack and operate upon the other of said means to permanently take up the slack on release of the brakes, said permanent take up and holding means including a housing and a plurality of dogs therein coacting with said strut. 120 125 130

5. In an automatic slack adjuster, in combination, a brake beam having a tension member, a strut interposed between the beam and tension member, a live lever having a bifurcated portion enclosing said strut, and permanent and temporary take up and holding means mounted upon the strut and associated with the live lever, one of said means being operative on application of the brakes 10 to temporarily take up the slack and operate upon the other of said means to permanently take up the slack on release of the brakes, said temporary and permanent take up and holding means including a housing, 15 a dog coacting with the strut, and a spring holding the dog in canted relation whereby it is freely moved in one direction relatively to the strut to hold it against movement in the opposite direction.
- 20 6. In an automatic slack adjuster, in combination, a live lever having a bifurcated portion, permanent take up and holding means interposed in the bifurcated portion of said lever, a rod passing through said holding means, a temporary take up and holding means mounted upon said rod, and a spring interposed between said two holding means.
- 25 7. In an automatic slack adjuster, in combination, a live lever having a bifurcated portion, permanent take up and holding means interposed in the bifurcated portion of said lever, a rod passing through said holding means, a temporary take up and holding means mounted upon said rod, a spring interposed between said two holding means, and a link interposed between the live lever and the housing of the temporary take up and holding means adapted to move 30 said temporary take up and holding means when said live lever exceeds its predetermined travel.
- 35 8. In an automatic slack adjuster, in combination, a live lever having a bifurcated portion, permanent take up and holding means interposed in the bifurcated portion of said lever, a rod passing through said holding means, a temporary take up and holding means mounted upon said rod, a spring interposed between said two holding means, and a link interposed between the live lever and the housing of the temporary take up and holding means adapted to move 40 said temporary take up and holding means when said live lever exceeds its predetermined travel.
- 45 9. In an automatic slack adjuster, in combination, a bifurcated live lever, a rod passing through said live lever adapted to be associated with the brake beam, temporary take up and holding means mounted upon said rod, a link connecting said means with said live lever for moving said means along said rod on excess travel, a spring adapted to be compressed during application of the brakes when excess travel occurs, and means actuated by said spring on release of the 50 brakes for permanently taking up and holding the excess travel.
- 55 10. In an automatic slack adjuster, in combination, a bifurcated live lever, a rod passing through said live lever adapted to be associated with the brake beam, temporary take up and holding means mounted upon said rod, a link connecting said means with said live lever for moving said means along said rod on excess travel, a spring adapted to be compressed during application of the brakes when excess travel occurs, and means actuated by said spring on release of the 60 brakes for permanently taking up and holding the excess travel, said last means including a housing mounted upon said rod between the bifurcated portion of said live lever, having holding dogs coacting with said rod.
- 65 11. In an automatic slack adjuster, in combination, a bifurcated live lever, a rod passing through said live lever adapted to be associated with the brake beam, temporary take up and holding means mounted upon said rod, a link connecting said means with said live lever for moving said means along said rod on excess travel, a spring adapted to be compressed during application of the brakes when excess travel occurs, and means actuated by said spring on release of the 70 brakes for permanently taking up and holding the excess travel, said last means including a housing mounted upon said rod between the bifurcated portion of said live lever, having holding dogs coacting with said rod.
- 75 12. In an automatic slack adjuster, in combination, a bifurcated live lever, a rod passing through said live lever adapted to be associated with the brake beam, temporary take up and holding means mounted upon said rod, a link connecting said means with said live lever for moving said means along said rod on excess travel, a spring adapted to be compressed during application of the brakes when excess travel occurs, and means actuated by said spring on release of the 80 brakes for permanently taking up and holding the excess travel, said last means including a housing mounted upon said rod between the bifurcated portion of said live lever, having holding dogs coacting with said rod, and means for regulating the brake shoe clearance.
- 85 13. In an automatic slack adjuster, in combination, a bifurcated live lever, a rod passing through said live lever adapted to be associated with the brake beam, temporary take up and holding means mounted upon said rod, a link connecting said means with said live lever for moving said means along said rod on excess travel, a spring adapted to be compressed during application of the brakes when excess travel occurs, and means actuated by said spring on release of the 90 brakes for permanently taking up and holding the excess travel, said last means including a housing mounted upon said rod between the bifurcated portion of said live lever, having holding dogs coacting with said rod, and means for regulating the brake shoe clearance.
- 95 14. In an automatic slack adjuster, in combination, a bifurcated live lever, a rod passing through said live lever adapted to be associated with the brake beam, temporary take up and holding means mounted upon said rod, a link connecting said means with said live lever for moving said means along said rod on excess travel, a spring adapted to be compressed during application of the brakes when excess travel occurs, and means actuated by said spring on release of the 100 brakes for permanently taking up and holding the excess travel, said last means including a housing mounted upon said rod between the bifurcated portion of said live lever, having holding dogs coacting with said rod, and means for regulating the brake shoe clearance.
- 105 15. In an automatic slack adjuster, in combination, a bifurcated live lever, a rod passing through said live lever adapted to be associated with the brake beam, temporary take up and holding means mounted upon said rod, a link connecting said means with said live lever for moving said means along said rod on excess travel, a spring adapted to be compressed during application of the brakes when excess travel occurs, and means actuated by said spring on release of the 110 brakes for permanently taking up and holding the excess travel, said last means including a housing mounted upon said rod between the bifurcated portion of said live lever, having holding dogs coacting with said rod, and means for regulating the brake shoe clearance.
- 115 16. In an automatic slack adjuster, in combination, a bifurcated live lever, a rod passing through said live lever adapted to be associated with the brake beam, temporary take up and holding means mounted upon said rod, a link connecting said means with said live lever for moving said means along said rod on excess travel, a spring adapted to be compressed during application of the brakes when excess travel occurs, and means actuated by said spring on release of the 120 brakes for permanently taking up and holding the excess travel, said last means including a housing mounted upon said rod between the bifurcated portion of said live lever, having holding dogs coacting with said rod, and adjusting means for determining the distance said live lever shall travel before said slack adjuster means goes into operation.
- 125 In testimony whereof I affix my signature.
- WILLIAM H. SAUVAGE.
